CLAIM

The ornamental design for a hip seat for baby, as shown and described.

DESCRIPTION

FIG. 1 is a first front perspective view of a hip seat for baby showing the design in a first configuration of use;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second front perspective view of the hip seat for baby showing the design in a second configuration of use;

FIG. 9 is a left side view of the design in the second

configuration of use shown in FIG. 8; and,

FIG. 10 is a detail view of a lower portion of the second front perspective view of the design in the second configuration of use shown in FIG. 8.
